CLAIM

The ornamental design for a package for food products, as shown and described.

DESCRIPTION

FIG. 1 is an isometric view of a package for food products. FIG. 2 is a front elevation view of the package for food products of FIG. 1.

FIG. 3 is a rear elevation view of the package for food products of FIG. 1.

FIG. 4 is a left side elevation view of the package for food products of FIG. 1.

FIG. 5 is a right side elevation view of the package for food products of FIG. 1.

FIG. 6 is a top plan view of the package for food products of FIG. 1; and,

FIG. 7 is a bottom view of the package for food products of FIG. 1.

The claim is limited to the shaded surfaces only. Portions of FIGS. 1 through 7 are shown in broken lines illustrating portions of the article that form no part of the claimed design. The broken lines immediately adjacent the shaded surfaces represent boundaries of the claim and form no part thereof.

1 Claim, 7 Drawing Sheets
